UNITED STATES PATENT OFFICE.

WILLIAM L. EVANS, OF BRIDGETON, NEW JERSEY.

DESIGN FOR A DISH.

No. 38,888.

Specification for Design.

Patented Nov. 19, 1907.

Application filed August 24, 1907. Serial No. 390,058. Term of patent 14 years.

To all whom it may concern:

Be it known that I, WILLIAM L. EVANS, a citizen of the United States, residing at Bridgeton, in the county of Cumberland and State of New Jersey, have invented a new, original, and ornamental Design for Dishes, of which the following is a specification, reference being had to the accompanying drawing, forming part thereof.

The figure is a perspective view of the dish, showing my new design.

I claim:

The ornamental design for a dish, as shown.
